US00D614230S

(12) **United States Design Patent**
Hidaka

(10) **Patent No.:** **US D614,230 S**
(45) **Date of Patent:** **** Apr. 20, 2010**

(54) **PAYMENT TERMINAL**

(75) Inventor: **Masataka Hidaka**, Fukuoka-ken (JP)

(73) Assignee: **Panasonic Corporation**, Osaka (JP)

(**) Term: **14 Years**

(21) Appl. No.: **29/342,957**

(22) Filed: **Sep. 3, 2009**

(30) **Foreign Application Priority Data**

Mar. 3, 2009 (JP) 2009-004592

(51) **LOC (9) Cl.** **18-01**

(52) **U.S. Cl.** **D18/12; D18/4.6**

(58) **Field of Classification Search** ..... D14/218, D14/336, 341-347, 371-376, 387; D18/1, D18/2, 3.1-3.3, 4.1-4.6, 5-12, 12.1-12.3; D21/324, 329, 332, 512; D99/28, 34-38, D99/40; 235/1 E, 2, 7 R, 12, 22, 33, 51, 235/52, 58 R, 59 A, 59 BC-59 BH, 59 CP, 235/59 T, 59 TP, 61 R

(57) **CLAIM**

The ornamental design for a payment terminal, as shown and described.

DESCRIPTION

FIG. 1 is a top perspective view of a payment terminal, showing the present invention;

FIG. 2 is a top view thereof;

FIG. 3 is a rear view thereof;

FIG. 4 is a first side view thereof;

FIG. 5 is a second side view thereof;

FIG. 6 is a front view thereof; and,

FIG. 7 is a bottom view thereof.

The broken lines depict environmental subject matter only and form no part of the claimed design.
